Attorney.

Patented Aug. 7, 1928.

UNITED STATES PATENT OFFICE.

CHARLES H. ALLEN, OF CLAREMONT, NEW HAMPSHIRE, ASSIGNOR TO SULLIVAN MACHINERY COMPANY, A CORPORATION OF MASSACHUSETTS.

ROCK-DRILLING MOTOR.

Application filed April 7, 1922. Serial No. 550,460.

My invention relates to motors and more particularly to rock drilling motors of the percussive type.

An object of my invention is to provide 5 an improved motor. Another object of my invention is to provide an improved motor in which extreme rapidity of reciprocation may be obtained. A further object of my invention is to provide an improved motor 10 for rock drilling purposes in which by reason of increased speed and power of reciprocation of the piston, the speed of drilling may be very materially increased. A still further object of my invention is to provide an 15 improved valve mechanism for motors and especially adapted for rock drilling motors. Other objects and advantages of my invention will, however, hereinafter more fully appear.

20 In the accompanying drawings I have shown for purposes of illustration one form which my invention may assume in practice.

In these drawings, —

Fig. 1 is a central vertical longitudinal section through the valve mechanism and 25 motor cylinder of a motor in which the illustrative embodiment of my invention is incorporated.

Fig. 2 is a similar view with the moving 30 parts of the motor shown in different position.

In the form of my invention shown for purposes of illustration in the accompanying drawings, I provide a cylinder 1 in whose bore 2 a piston 3 is reciprocable, 35 this piston having a striking bar 4 of well known construction connected thereto. The opposite ends of the cylinder are closed by heads 5 and 6 and from the head 6 a suitable rifle bar 7 projects, this rifle bar extending 40 into this piston and controlling its movement.

For the purpose of causing reciprocation of the piston, suitable distributing passages 45 9 and 10 lead to points adjacent the opposite ends of the cylinder, the passage 9 leading to the front end of the cylinder, while the passage 10 leads to the rear end thereof. The supply and exhaust of fluid through the distributing passages 9 and 10 is controlled by 50 a valve mechanism generally indicated by

11 and comprising a casing 12 in which suitable bushings 13 are arranged in such manner as to form a chamber having end portions 14 of smaller diameter than its 55 central portion 15. The passages 9 and 10 communicate with the valve chamber adjacent the ends of the central enlarged bore 15, the passage 9 communicating as at 16 and the passage 10 as at 17, there being annular grooves 18 formed adjacent the shoulders 19 which constitute the ends of the enlarged bore 15, which grooves communicate with the ports 16 and 17 and so with the passages 9 and 10. Adjacent the remote 60 ends of the smaller portions 14, ports 20 and 21 connect throwing passages 22 and 23 with the valve chamber, these passages at their opposite ends communicating with the bore of the cylinder 2 by a plurality of ports, 70 the passage 22 communicating with the cylinder at a point spaced a relatively short distance from the position of the rear end of the piston when the latter is in its steel engaging position by a port 24 and also 75 having a smaller port 25 connected with the passage 22 by a passage 26 and opening into the bore of the cylinder at a point materially nearer the rear end thereof. The passage 23 opens into the bore of the cylinder for 80 ward of the middle thereof, by a pair of ports 27 and 28 which are connected by a passage 29, the port 27 being the main throwing port and the port 28 which is materially smaller, being spaced a substantial distance 85 nearer the front end of the cylinder. Intermediate the ports 16 and 20 and 17 and 21 respectively in the valve chest, there are formed annular grooves 30 and 31, which 90 grooves communicate by ports 32 and 33 with an exhaust passage 34 formed in a box like member 35 secured to the valve chest. Within the valve chest is a valve of the three-spool type, this valve being designated 36 and comprising end spools or heads 95 37 and 38 fitting the bores 14 and a central spool 39 of slightly larger diameter fitting the bore 15, the heads 37 and 38 being connected respectively with the spool 39 by reduced portions 40 and 41. The ends of the 100 heads 37 and 38 are hollowed out as indicated at 42 and buffer plugs 43 arranged in the

ends of the chambers 14 limit the throw of the valve, these extending into the recesses 42. The buffer plugs are laterally grooved as indicated at 44 and these plugs are also traversed by axially extending vent ports 45 of small size, these ports being of less flow area than that of the ports 25 and 28 and passages 26 and 29. The plugs are of a diameter to nearly fill the bores 42 in the heads 37 and 38, but the grooves 44 permit the ready supply and escape of fluid from between the ends of the valve and the buffers, while the vents 45 facilitate the movements of the valve towards the buffers and by providing leak means when the valve moves out of contact with the buffers prevents too early throwing when by reason of hard rotation the rearward stroke of the piston (during which the partial rotation given the piston occurs) is slowed down and the interval between the opening of ports 28 and 27 is increased. Premature throwing due to leakage past the edge of the piston when the parts are worn is also prevented by this feature. A fluid pressure supply port 46 communicates with an annular space 47 formed between the ends of the bushings 13 in the central part of the valve chest.

Having now described the structure of the illustrative form of my invention, I will point out its mode of operation. Assuming the parts to be in the position shown in Fig. 1, that is with the valve 36 in a position with its head 37 against the forward stop plug 43, it will be observed that motive fluid is passing from the port 46 and annular space 47 to the left of the head 39 and, by way of port 17 and passage 10, to the rear end of the piston 3 to cause a forward movement thereof. Simultaneously the front end of the cylinder is connected to exhaust by way of passage 9, port 16, annular port 30, and port 32. The piston 3 will accordingly move forward, and during its forward travel, will first overrun the port 25. This port is of such size as to permit the supply of sufficient air to the passage 22 to substantially fill that passage and the space in front of the head 37 of the valve with air just about as the throwing port 24 is uncovered by the piston. Accordingly, the valve will be thrown over sharply on opening of the port 24 and by reason of the preliminary filling of the passages, and then the uncovering of the relatively large throwing port, it is possible to get a much faster travel of the valve than heretofore, and accordingly a higher rate of operation of the entire motor since less time will obviously be lost in valve travel which must occur before a reversal of direction of the piston can take place. However the passages 24, 25 and 27, 28 are of such size and are so spaced longitudinally of the cylinder that the valve is not thrown until the ports 24, 25 or 27, 28

are both uncovered by the piston. Were no auxiliary ports such as 25 and 28 to be employed there would be either too early throwing of the main valve with resultant loss of power by too prompt cutting off of the air and cushioning or a slowing down in strokes per minute. By using the auxiliary ports there is no sudden pressure drop in the rear end of the cylinder when the port 24 opens as the throwing passage is already filled, an additional advantage. After the valve 36 is moved to the position shown in Fig. 2, when a sufficient pressure has been admitted to the front end of the cylinder by way of port 16 and passage 9, the return stroke of the piston will take place, it being noted that if the piston overruns the port 9 at the forward end of its travel, the air entrapped between the front end of the piston and the head 5, either alone or with the aid of the rebound of the piston from the steel, will cause the piston to travel back far enough to permit the flow of pressure fluid through the passage 9 to its front surface. During ordinary drilling with the steel well back in the chuck, i. e. with the drill held up properly to the work, port 9 will not ordinarily be covered by the piston, but will be covered by the piston when the drill is running idly. The piston will move backwards on its rearward stroke and first uncover the port 28 which will transmit a sufficient pressure to fill up the passage 23 and the space to the front end of the valve chest before the port 27 is uncovered and accordingly with the opening of the port 27 a quick, sharp reversal of the valve 36 will take place. It will of course be understood that during the rearward travel of the piston, the rear end of the cylinder is connected by passage 10, port 17, groove 30, and port 33 with the exhaust. When rotation is hard the air transmitted through port 28 would tend to throw the valve before the port 27 is reached by the slow moving piston but by reason of the vent 45 as soon as the valve begins to move the resultant opening of the vent will give the necessary delay to permit a full rear stroke, it being noted that live pressure on the unbalanced area of the middle spool resists the valve movement. While, of course, the relative areas of passages which I shall now describe are not that best calculated for all drills, in a drill of substantially the proportions shown, I have found that if the area of the ports 25 and 28 is made about one third the area of the main throwing ports and the ports are spaced in the general manner shown, it is possible to increase the drilling speed of a motor of the type herein illustrated quite 20% over its speed when employed with the ordinary single throwing ports. This is obviously a most desirable improvement as prior to the provision of my improved construction a motor

of the type illustrated was equal to the best of equal cylinder size and piston weight, and by reason of my invention, a considerable margin of superiority over any motor of which I am now aware is produced.

While I have in this application specifically described one form which my invention may assume in practice, it is understood that this form of the same is shown for purposes of illustration and that the invention may be modified and embodied in various other forms without departing from its spirit or the scope of the appended claims.

What I claim as new and desire to secure by Letters Patent is:

1. In a fluid pressure motor, a cylinder, a piston reciprocable therein, means forming distributing passages communicating with said cylinder adjacent the ends thereof, a valve controlling said passages, and means for controlling said valve by the fluid in the ends of the cylinder which directly actuates the piston comprising throwing passages each communicating with the bore of the cylinder by a smaller port nearer the end thereof and a larger port nearer the center thereof.

2. A pressure fluid motor having a cylinder, a piston therein and a fluid actuated distributing valve, main and auxiliary passage means adapted to allow communication between each end of said valve and said cylinder, said valve being subjected to an initial pressure due to said auxiliary means, and means for preventing said auxiliary means from allowing a pressure to be built up great enough to throw said valve.

3. In a fluid pressure motor, a cylinder, a piston reciprocable therein, means for effecting reciprocation of said piston including a valve chest, a valve therein, buffers limiting movement of said valve, passage means leading from said chest and controlled by said valve for supplying and exhausting fluid with respect to each end of said cylinder, means for effecting movement of said cylinder, means for effecting main and auxiliary passage means connecting said chest with said cylinder and communicating with the latter at longitudinally spaced points, said auxiliary passage means being disposed nearer the end of the cylinder and said main passage means being disposed nearer the center thereof, and means comprising passage means formed in said buffers for venting each end of said valve for preventing said auxiliary passage means from allowing a pressure to be built up great enough to throw said valve prior to the opening of said main passage means.

4. A pressure fluid motor having a cylinder, a piston reciprocable therein, a fluid distribution valve, means forming main and auxiliary passage means adapted to allow

communication between each end of the valve and the cylinder, said valve being subjected to an initial pressure due to said auxiliary passage means, and means comprising passage means for venting each end of said valve for preventing said auxiliary means from allowing the pressure to be built up great enough to throw said valve prior to the opening of said main passage means.

5. In a fluid pressure motor, a cylinder, a piston reciprocable therein, means for effecting reciprocation of said piston including a valve chest, a valve therein, said valve having a recessed head, a buffer limiting movement of said valve, passage means leading from said chest and controlled by said valve for supplying and exhausting fluid with respect to one end of said cylinder, means for effecting movement of said valve including a passage connecting said chest with said cylinder and communicating with the latter by means of a main and an auxiliary port at points spaced longitudinally of the cylinder, and passage means formed in said buffer for venting one end of said valve for preventing premature throwing thereof, said passage means being of lesser flow area than said auxiliary port.

6. In a fluid pressure motor, a cylinder, a piston reciprocable therein, means forming distributing passages communicating with said cylinder adjacent the ends thereof, a valve controlling said passages, means for controlling said valve comprising throwing passages each communicating with the cylinder by main and auxiliary ports of different size at points spaced longitudinally thereof, and means comprising vent ports for each end of said valve for preventing said auxiliary ports from allowing a pressure to be built up great enough to throw said valve prior to the opening of said main throwing ports.

7. In a fluid pressure motor, a cylinder having a bore in which a piston is reciprocable, fluid supply and exhaust means therefore including distribution passages leading to points adjacent the ends of said cylinder, valve means controlling the communication of said distribution passages with a source of fluid pressure and with exhaust including a valve chest with which said passages communicate, said valve chest also having supply and exhaust ports communicating therewith, a multiple spool valve reciprocable in said chest, and means for controlling said valve by the fluid in the ends of the cylinder which directly actuates said piston comprising throwing passages respectively communicating with said chest and with the bore of said cylinder, each of said throwing passages having communication with the bore of the cylinder at

points spaced longitudinally of the cylinder, the communication at points more closely adjacent the center of the cylinder being substantially less restricted than at points more remote therefrom and the communication of said passages with the cylinder and their volume being proportioned to permit

the building up of pressure, during the period intermediate initial communication and less restricted communication, sufficient to balance the valve.

In testimony whereof I affix my signature.

CHARLES H. ALLEN.
